CLAIM

The ornamental design for a combined article holder and advertising card holder, as shown and described.

DESCRIPTION

FIG. 1 is a front elevational view of a combined condiment rack and card holder showing my new design, the rear view being a mirror image;

FIG. 2 is a top plan view thereof;

FIG. 3 is a bottom plan view thereof;

FIG. 4 is a right side elevational view thereof;

FIG. 5 is a left side elevational view thereof; and

FIG. 6 is a front elevational view thereof showing cards inserted therein.

*FIG. 2**FIG. 1**FIG. 4**FIG. 3**FIG. 5*

FIG. 6
